(57) **CLAIM**

The ornamental design for an actuator for a pocket knife, as shown and described.

DESCRIPTION

FIG. 1 is a right, rear perspective view of the actuator for a pocket knife embodying the new design;

FIG. 2 right, front perspective view of the actuator for a pocket knife embodying the new design;

FIG. 3 is a right side elevation view of the actuator for a pocket knife;

FIG. 4 is a left side elevation view of the actuator for a pocket knife;

FIG. 5 is a top side elevation view of the actuator for a pocket knife;

FIG. 6 is a bottom side elevation view of the actuator for a pocket knife;

FIG. 7 is a front side elevation view of the actuator for a pocket knife; and,

FIG. 8 is a rear side elevation view of the actuator for a pocket knife.

The broken lines in the drawings represent portions of the actuator for a pocket knife that form no part of the claimed design.
